DESIGN FOR A CLOTHESPIN

Herbert E. Rhodes, La Mesa, Calif.

Application October 16, 1945, Serial No. 122,869

Term of patent 7 years

(Cl. D17—6)

To all whom it may concern:

Be it known that Herbert E. Rhodes, a citizen of the United States of America, residing at La Mesa, in the county of San Diego and State of California, has invented a new, original, and ornamental Design for Clothespin, of which the following is a specification, reference being had to the accompanying drawing, forming a part thereof.

Fig. 1 is a top end view of a clothespin showing my new design;

Fig. 2 is a side elevational view;

Fig. 3 is a lower end view; and

Fig. 4 is a side elevational view of the same, rotated 90 degrees from the disclosure in Fig. 2.

I claim:

The ornamental design for clothespin, substantially as shown.

HERBERT E. RHODES.
